WALL MOUNTED ROOM HEATER

Herbert M. Reeves, Kankakee, and John B. Mathis, Chicago, Ill., assignors, by mesne assignments, to Heil Quaker Corporation, a corporation of Delaware

Application March 9, 1955, Serial No. 493,266

5 Claims. (Cl. 126—116)

This invention relates to room heaters and has particular reference to unvented gas burning heaters for wall mounting.

Unvented gas burning heaters are often employed as room heaters, sometimes being installed as permanent parts of the building structure and sometimes as free standing units. In many instances it is particularly desirable that the unit have the advantages of being affixed in place without requiring that it be recessed into the building wall or otherwise made a permanent part of the building structure. They must in any case amply meet both safety requirements and heating specifications. It is especially desirable that the unit be attractive so as not to detract from the room furnishings as well as require a minimum of floor space and interference with furniture placement.

It is therefore a primary object of the invention to provide an improved air circulating unvented gas fired room heater for mounting on a finished room wall.

It is a more particular object to provide a room heater having a low cabinet temperature and safely mountable on a room wall.

It is another object to provide an attractive room heater of an air circulating type which minimizes floor space and furniture arrangement problems.

It is still another object to provide an improved baffle and heating structure for a room air circulator.

It is a further object to provide an improved room heater for directing the mixture of heated air and products of combustion from a localized upper portion of the heater cabinet.

It is also an object to provide a wall mountable heater which is simply and inexpensively installed and maintained and which is safe and efficient in operation.

Briefly, in accordance with one aspect of my invention, the combustion chamber of a gas fired heater is vertically disposed and supported by a wall plate. Both the wall plate and the heater cabinet unit for it are shielded to permit air circulation from the bottom of the heater and up through and along the sides of the combustion chamber. The heated gases, i. e., the heated air and the products of combustion, are discharged in three zones at an upper front opening in the cabinet, these zones being respectively for the passage of the heated gases from the combustion chamber and from the front and back surfaces of the chamber, the heater cabinet itself remaining relatively cool.

The objects of the invention thus generally set forth, together with other objects and ancillary advantages are attained by the construction and arrangement shown by way of illustration in the accompanying drawings in which:

Figure 1 is a front view of a gas heater assembly incorporating the invention with portions cut away to better illustrate the arrangement of the components.

Fig. 2 is a side view of the assembly of Fig. 1 also with portions of the cabinet cut away.

Fig. 3 is a top view of the heater of Fig. 1.

2

Figs. 4 and 5 are perspective views of the assembly of Fig. 1, Fig. 5 showing the wall plate assembly in place and Fig. 4 showing the cabinet and shield assembly removed from the wall plate assembly.

5 Fig. 6 is a view of the wall plate of the heater.

Fig. 7 is a detail of the wall plate construction of Fig. 6.

Fig. 8 is a detail view showing the mounting of the wall plate of Fig. 6 to a wall.

Fig. 9 is a perspective view of a mounting clip employed on the wall plate of Fig. 6.

Fig. 10 is a perspective view of the combustion chamber air chute.

Fig. 11 is a top view of the cabinet lower fastening means; and

15 Fig. 12 is a side view of the lower fastening means of Fig. 11.

While the invention is susceptible of various modifications and alternative constructions, there is shown in the drawings and will herein be described in detail the preferred embodiment. It is to be understood that it is not thereby intended to limit the invention to the form disclosed, but it is intended to cover all modifications, alternative constructions, and equivalents falling within the spirit and scope of the invention as expressed in the appended claims.

Referring now to the drawings and particularly Figs. 1 and 2 and 4 and 5, a wall-mountable heater embodying my invention may be seen as having as one major sub-assembly, a wall plate assembly 1 (Fig. 4). Major components of this assembly are the gas supply and control system 2, the burner assembly 3, and the combustion chamber assembly 4. The other major sub-assembly is the cabinet 5 (Fig. 5) which fits over the wall plate assembly and which may be noted in passing as having an upper front heated air discharge opening 6 screened by a grill and a louvered lower access panel 7 at the lower air intake end of the cabinet. Since the heat shield arrangement is closely incorporated in the structure of both major sub-assemblies, it is not generally indicated at this point but its description and function will be made apparent as the description proceeds. While the drawings are not made exactly to scale, an appreciation of the general dimensions may be gained therefrom, the particular embodiment described in the drawings having a vertical dimension of 4 feet, and being suitably mounted about 6 to 12 inches above the floor on a finished wall of the room to be heated.

Describing first the wall plate assembly 1, the back panel 8, suitably made of sheet metal and best illustrated 50 in Fig. 6 is designed to be mounted directly on the room wall and to support the remainder of the assembly. This back panel has two vertical rectangular channels 9 formed near the vertical side edges to stiffen the panel. The top hanger 10, formed as a channel section with end 55 surfaces 11, is spaced slightly above the back plate 8 so that the long horizontal slot between them can be employed for placement of mounting screws at any place along the length. For ease and economy of fabrication, this top channel is separately formed and connected to the back plate 8 by adapter channel sections 12 of the back plate. These channel sections are welded on each open end 11 of the top hanger channel 10 and to the channels 9 of the backplate. The top hanger member has an upper lip 13 which is bent back from the top channel edge and thus away from the wall serve as an upper cabinet support as later described.

To hold the back plate in place, a pair of top clamps 14, suitably made of sections of bent steel are employed. The upper portion of each clamp engages the top channel 10 of the hanger and the bent lower flange of the clamp presses the edge of the back panel 8 firmly against the wall. The clamps are provided with apertures 15

so that they may be held by wall screws anywhere along the slot opening between the top channel 10 and the back plate 8. The clamps may thus be screwed to the wall studs under the finished surface while still permitting some latitude in the position of the wall plate. One or more bottom clamps are similarly provided, at least one clamp 17 being screwed to the wall under the center portion of the lower edge of the back panel 8. This clamp also has an out-turned flange to serve for latching the bottom of the cabinet, as will be later described. For rigidity of the structure, an angle or channel member 18 is also welded across the bottom back panel 8 between the vertical channels 9 formed therein.

In order to support a back liner or heat shield and the combustion chamber, four outstanding brackets or tabs 19 are provided, two being welded to upper and lower positions of each vertical channel 9 at the back panel 8. These brackets have a bent-over mounting flange 20 which is suitably welded to the channels. As may be seen in Fig. 9, the tabs also have holding ears 21 and 22, the innermost ear 21 being pushed out to space a panel fitted over the tab a given distance from the back panel 8 itself. A smaller tab 23 projects from the end of the main bracket or tab 19 supporting the combustion chamber.

The back liner or heat shield 24, is generally rectangular in shape with bent-up side flanges 25. The four slots in the back liner are aligned with the tabs 19 so the back panel may be positioned over them. This panel is spaced from the wall and the wall panel 8 by the inner bracket ears 21, thus shielding the wall from excessive heating. The bracket ears 22 are bent over the back liner after it is added to the wall plate of Fig. 6 to retain the liner in place.

The combustion chamber 4 is formed of two sheet metal members, a back sheet 27 and a front sheet 28 having bent-over side flanges 29. The chamber sheet members are provided with aligned slots for receiving the smaller stepped tabs 23 of the brackets 19.

The chamber 4 is thus simply assembled, spaced from the back liner 24, and held in place by slipping the sheets 27 and 28 over the outer tabs 23 and bending the tabs over. The combustion chamber panels 27 and 28 are preferably corrugated to stiffen them so that the chamber will hold its flat, vertically elongated shape when subjected to the high temperatures of burning gases.

The upper end of the combustion chamber is open and an air chute or hood 31 is mounted at the top thereof. This hood has a forwardly curved back member 32 which is fastened at its lower end to the back sheet 27 of the combustion chamber, and has side closures 33, suitably in a form approaching a circle quadrant. The chute thus formed is narrower than the space between the side flanges 25 of the back liner 24 so as to separate the directly heated air flowing upwardly and forwardly out of the combustion chamber from the indirectly heated air from the lateral sides and back surface of the chamber.

The burner assembly 3 suitably takes the form of a cast iron burner manifold which is elongated to present an array of gas orifices 34 just below the lower open end of the combustion chamber 4. The burner is suitably supported by a bracket 35 which is secured to the combustion chamber and a drip tray 36 is provided below the burner to protect the room floor from any falling combustion particles. A conventional air shutter 37 is provided at the burner entrance and a gas tubing section supplies gas from the supply control system 2. The latter suitably includes a temperature regulator unit 38, a safety shut-off 39, and a pilot light 40 for the burner. Obviously, of course, the fuel supply system may be varied to meet the particular economic or heating code requirements of each installation.

Reference is now made to the cabinet assembly 5 which fits over the wall-mounted assembly 1. As previously

mentioned, the cabinet assembly includes at its front surface a discharge opening 6 and a lower louvered access panel 7 which, together with a center solid panel 41 forms the front surface of the cabinet. The cabinet side panels 42 have a suitably curved front portion 43 for attractiveness of the assembly, together with inner bent-over rear flanges 44. A top panel 45 likewise has an attractively curved, bent-over front section 46 and an inner rear flange 47, the panels being suitably welded together to form a sturdy enclosure. No bottom panel is employed, however, in order that air may enter from the floor into the combustion chamber and along either side of it in addition to such air as enters through the louvered front panel portion 7.

Part of the liners or baffling system of the wall heater are incorporated within the cabinet assembly 5. Thus a front liner 48 is employed, this liner extending along a central portion of the inner surface of the cabinet. Side flanges 49 extend parallel to the cabinet sides. This liner is spaced from the cabinet and shields the cabinet from direct radiation of heat energy from the combustion chamber. The upper end of the front liner or shield 48 terminates somewhat above the lower limit of the front discharge opening so that an upper portion of the chamber extends above the liner and faces the lower portion of the front opening. Side liners 50 are also extended above the front liner flanges 49, these liners being positioned at both sides of the cabinet but spaced from its side walls. A curved top shield or baffle 51 is welded or otherwise secured to the curved upper end surfaces of the liners 50 to form a second air chute having its upper surface directed outwardly near the top of the discharge opening of the front panel. An additional curved heat shield or baffle 52 prevents heated air from being trapped in the upper part of the cabinet adjacent the wall and comprises a sheet metal member fastened between the side walls of the cabinet above the curved top shield 51 with its front portion extending to top of the front discharge opening of the cabinet.

When the front cabinet 5 is installed by positioning it over the wall plate 1, the combustion chamber air chute is directed toward the central level of the discharge opening of the cabinet. The air chute 51 fastened to the cabinet is spaced above the combustion chamber chute with its lower end adjacent the rear liner 24 of the wall plate assembly 1. The lower portion of the discharge opening extends below the combustion chamber air chute 31 and somewhat below the top portion of the combustion chamber. Thus it may be seen that the directly heated mixture of air and products of combustion from the combustion chamber is directed out of a central zone of the discharge opening. The combustion chamber also acts as a heat exchanger so that air rising between the front surface 28 of the chamber and the front liner 48 of the cabinet is discharged in the lower zone of the discharge opening. Likewise, the air rising between the back surface 27 of the combustion chamber and the back liner 24, together with the air along the lateral sides of the combustion chamber is directed by the chute 51 mounted on the cabinet assembly from the upper zone of the discharge opening. The top baffle plate 52 previously mentioned minimizes sooting of the room wall which might otherwise be caused by entrapment of the air in the top of the cabinet next to the wall. The cabinet itself is not a radiator, the front and rear liner preventing the cabinet and the wall from being appreciably heated by the combustion chamber.

For maximum control of the discharged heated air the upper surfaces of the air chutes 32 and 51 extend outwardly a distance beyond the discharge opening 6 an a grill for screening the opening and deflecting the air is provided. This grill is made of an expanded sheet metal in which the metal web portions are at an angle to the plane of the sheet so as to help deflect the discharged air downwardly. The grill is further made

three sections 53 and correspond to the three heating zones previously mentioned. Each section is horizontally curved or bent to have an outermost surface near the top of the zone. This outermost portion accommodates the protruding front edges of the air chutes 32 and 51. The heated air is directed outwardly and downwardly so that despite the height of the discharge grill from the floor, the heating action is made pleasant and effective. At the same time, with the heater dimensions mentioned, furniture placement near the heater is not handicapped and the heater is, of course, due to its particular arrangement, safe to touch because of its low cabinet temperature.

When installing the heater, the mounting screws hold the clamps of the wall plate assembly 1 and position the back plate.

The cabinet assembly 5 is then simply lifted so that the top flange 47 slips over and behind the upper inclined lip 13 of the frame hanger 10. The baffles 51 and 52 in the cabinet are self-aligning with the wall mounted assembly. The inner flanges 44 of the cabinet then rest against the wall.

To prevent the cabinet from rattling or being inadvertently opened, a bottom latch assembly is provided, this latch suitably taking the form of a rod 54 bent over an angle member 55 positioned between the sides 42 of the lower end of the cabinet. The rear end of the rod 54 is formed as a hook 56 to engage an aperture in the lower mounting bracket 17. Because the heater may not be centered on the bracket for some installations, it may be seen that the rod 54 can be simply slid along the lower frame channel 55 for alignment with the bracket 17.

We claim as our invention:

1. A wall mountable room heater comprising a wall plate assembly having a back panel mountable on a wall, upstanding support tabs vertically spaced along each vertical side of the back panel, a rear plate mountable over said support tabs and spaced from said rear panel, a combustion chamber defined by a pair of spaced metal plates closed along their vertical side edges and mountable on the ends of said tabs and spaced from said rear member, an elongated gas burner supported from said combustion chamber at the lower open end thereof, a first hood supported adjacent the top open end of the combustion chamber for directing the combustion products outwardly away from the wall plate, and a front cabinet enclosure mountable on said wall plate, said cabinet having a lower opening for admitting cool air and an upper front discharge opening through which said first hood extends for directing the heated gases rising from the combustion chamber and the heated air rising in front of the combustion chamber into the room, and a second hood extending through said discharge opening near the top thereof above the first hood.

2. A wall mountable room heater comprising a vertical wall plate adapted to be hung on a room wall, a rear vertical shield supportingly spaced from said wall plate, means defining a vertically elongated combustion chamber having spaced front and rear vertically extending metal walls further supportingly spaced from the wall plate, said chamber being open at its upper and lower ends, a gas burner mounted at the lower chamber end, a first deflecting hood at the upper chamber end extending forwardly from the rear wall of the chamber to deflect the heated gases rising from the combustion chamber, a cabinet enclosure mountable on said wall plate having an upper front discharge opening with a central zone aligned with said first hood to permit the outward flow of heated air from the combustion chamber, a second hood incorporated in said cabinet enclosure and positioned above the first hood and the rear vertical shield when the cabinet is mounted on the wall plate to deflect heated air rising between the rear shield and the rear combustion chamber wall to the discharge opening above the central zone, and an inner front vertical

shield supportingly spaced from the cabinet below the front opening to confine and direct the heated air rising along the front wall of the chamber until it passes through the discharge opening below said first hood.

- 5 3. A wall mountable room heater comprising a vertical wall plate adapted to be hung on a room wall, a rear vertical shield supportingly spaced from said wall plate, means defining a vertically elongated combustion chamber having spaced front and rear vertically extending metal walls further supportingly spaced from the wall plate, said chamber being open at its upper and lower ends, a gas burner mounted at the lower chamber end, a first deflecting hood at the upper chamber end extending forwardly from the rear wall of the chamber to deflect the heated gases rising from the combustion chamber, a cabinet enclosure removably mountable on said wall plate, a grill incorporated in the upper front portion of the cabinet having upper, central, and lower air outlet zones, said central grill zone being aligned opposite the first hood to permit the outward flow of heated air rising through the combustion chamber, a second hood incorporated in said cabinet enclosure and positioned above the first hood and the rear vertical shield when the cabinet is mounted on the wall plate, 15 said upper grill zone being aligned opposite the second hood to permit the outward flow of heated air rising between the rear shield and the rear combustion chamber wall, and an inner front vertical shield supportingly spaced from the cabinet but below the top portion of the 20 combustion chamber, said lower grill zone having at least a portion aligned opposite the top of the front shield to facilitate the outward flow of heated air rising between the front shield and the front wall of the combustion chamber.
- 25 4. A wall mountable room heater comprising a vertical wall plate adapted to be hung on a room wall, a rear vertical shield supportingly spaced from said wall plate, a gas burner extending for substantially the width of the vertical shield spaced from the front of the vertical shield near its lower end and supported from the wall plate, a combustion chamber comprising front and rear vertical metal plates supported from the wall plate above the burner with the rear plate thereof spaced from the rear shield to permit the passage of air therebetween, 30 the upper end of the rear combustion chamber wall forming a forwardly extending hood, and a removable cabinet cover mountable on said wall plate having an upper front discharge opening through which the forward end of said hood extends at an intermediate level of the opening when the cabinet cover is mounted, to permit the outward flow of hot gases from the combustion chamber and heated air from the space in front of it, said cabinet cover having a lower opening to permit the entrance of air, a deflector extending across the width 35 of the cabinet cover and secured therein having its front portions extending slightly outwardly beyond the discharge opening near the top thereof and extending downwardly and rearwardly to meet the top of the rear vertical shield as a hood for assuring the discharge of indirectly heated air rising between the rear combustion chamber wall and the rear shield.
- 40 5. A wall mountable room heater comprising a vertical wall plate adapted to be hung on a room wall, a rear vertical shield supportingly spaced from said wall plate, a gas burner extending for substantially the width of the vertical shield spaced from the front of the vertical shield near its lower end and supported from the wall plate, a combustion chamber comprising front and rear vertical metal plates supported from the wall plate above the burner with the rear plate thereof spaced from the rear shield to permit the passage of air therebetween, 45 the upper end of the rear combustion chamber wall forming a forwardly extending hood, and a removable cabinet cover mountable on said wall plate having an upper front discharge opening through which the forward end of said hood extends at an intermediate level of the opening when the cabinet cover is mounted, to permit the outward flow of hot gases from the combustion chamber and heated air from the space in front of it, said cabinet cover having a lower opening to permit the entrance of air, a deflector extending across the width 50 of the cabinet cover and secured therein having its front portions extending slightly outwardly beyond the discharge opening near the top thereof and extending downwardly and rearwardly to meet the top of the rear vertical shield as a hood for assuring the discharge of indirectly heated air rising between the rear combustion chamber wall and the rear shield.
- 55 6. A wall mountable room heater comprising a vertical wall plate adapted to be hung on a room wall, a rear vertical shield supportingly spaced from said wall plate, a gas burner extending for substantially the width of the vertical shield spaced from the front of the vertical shield near its lower end and supported from the wall plate, a combustion chamber comprising front and rear vertical metal plates supported from the wall plate above the burner with the rear plate thereof spaced from the rear shield to permit the passage of air therebetween, 60 the upper end of the rear combustion chamber wall forming a forwardly extending hood, and a removable cabinet cover mountable on said wall plate having an upper front discharge opening through which the forward end of said hood extends at an intermediate level of the opening when the cabinet cover is mounted, to permit the outward flow of hot gases from the combustion chamber and heated air from the space in front of it, said cabinet cover having a lower opening to permit the entrance of air, a deflector extending across the width 65 of the cabinet cover and secured therein having its front portions extending slightly outwardly beyond the discharge opening near the top thereof and extending downwardly and rearwardly to meet the top of the rear vertical shield as a hood for assuring the discharge of indirectly heated air rising between the rear combustion chamber wall and the rear shield.
- 70 7. A wall mountable room heater comprising a vertical wall plate adapted to be hung on a room wall, a rear vertical shield supportingly spaced from said wall plate, a gas burner extending for substantially the width of the vertical shield spaced from the front of the vertical shield near its lower end and supported from the wall plate, a combustion chamber comprising front and rear vertical metal plates supported from the wall plate above the burner with the rear plate thereof spaced from the rear shield to permit the passage of air therebetween, the upper end of the rear combustion chamber wall forming a forwardly extending hood, and a removable cabinet cover mountable on said wall plate having an upper front discharge opening through which the forward end of said hood extends at an intermediate level of the opening when the cabinet cover is mounted, to permit the outward flow of hot gases from the combustion chamber and heated air from the space in front of it, said cabinet cover having a lower opening to permit the entrance of air, a deflector extending across the width 75 of the cabinet cover and secured therein having its front portions extending slightly outwardly beyond the discharge opening near the top thereof and extending downwardly and rearwardly to meet the top of the rear vertical shield as a hood for assuring the discharge of indirectly heated air rising between the rear combustion chamber wall and the rear shield.

ward end of said hood discharges heated gases from the combustion chamber and heated air from the space in front of it when the cabinet cover is mounted, said cabinet cover having a lower opening to permit the entrance of air, and upper and lower spaced deflectors extending across the width of the cabinet cover and secured therein having their front portions near the top of the discharge opening, the upper deflector extending downwardly and rearwardly to meet the wall plate as a hood for assuring the discharge of air rising between 10 the rear shield and the wall plate, and the lower deflector extending downwardly and rearwardly to meet

the top of the rear shield to serve as a hood for assuring the discharge of air rising between the rear wall of the combustion chamber and the rear shield.
